UNITED STATES PATENT OFFICE.

HENRY R. CASSEL, OF NEW YORK, N. Y.

BARREL-FILTER.

SPECIFICATION forming part of Letters Patent No. 722,399, dated March 10, 1903.

Application filed November 20, 1902. Serial No. 132,061. (No model.)

To all whom it may concern:

Be it known that I, HENRY R. CASSEL, a citizen of the United States, residing at New York city, (Manhattan,) county and State of New York, have invented certain new and useful Improvements in Barrel-Filters, of which the following is a specification.

This invention relates to an improved barrel-filter of the type generally used in the chlorination or lixiviation of ores.

My improved filter is so constructed that it will readily sustain the pressure of the ore within the rotating barrel, that it is not liable to become displaced or detached during use, and that it may be readily repaired.

In the accompanying drawings, Figure 1 is a longitudinal section of my improved barrel-filter; Fig. 2, a cross-section on line 2 2, Fig. 1; Fig. 3, a horizontal section of part of the filter on line 3 3, Fig. 2; Fig. 4, a longitudinal section of one of the transverse bars; Fig. 5, a similar section through one of the longitudinal bars; Fig. 6, an enlarged longitudinal section through one of the filling-tubes. Figs. 7 and 8 are cross-sections through modifications of the filter, and Fig. 9 a horizontal section through a further modification.

The letter *a* represents a rotatable ore-barrel, provided with a lead lining *a'* and supported by trunnions *a²* upon suitable bearings *b*.

a³ represents the usual manholes.

a⁴ is the water-inlet cock, and *a⁵* the discharge-cock.

Within the barrel *a* there is secured a filter, which is incased in lead, the lead casing of the filter being burned to the lead lining of the barrel. In this way the filter is made integral with the barrel-lining, so that it is held in position without additional supporting means, while, furthermore, creeping of material between barrel and filter is entirely prevented.

The filter is composed, preferably, of two rows of intersecting bars crossing each other at or about at right angles, each bar being formed of a rigid core and of a surrounding lead casing, which is burned to the barrel-lining.

c c represent the cores of the lower or transverse bars, the threaded ends of which pass through perforations of barrel *a* and are re-

movably secured thereto by nuts *c'*. Obviously, however, the cores may be made in the shape of screw-bolts, with a thread upon one end only. The cores *c* are surrounded by the lead casings or sleeves *c²*, the ends of which are preferably flanged, as at *c³*, so that the casing may be readily burned to and thus made integral with the lining *a'*.

The upper or longitudinal bars of the filter pass through the heads of the barrel and are made in all respects similar to the transverse bars. They are composed of the rigid threaded cores *d*, carrying nuts *d'*, and of the lead casings *d²*, having flanges *d³*, which are burned to the lining of the barrel-heads.

In order to reduce the size of the sieve mesh, I may place upon the lower bars and intermediate the upper bars a number of perforated lead filling-tubes *e*, the flanged ends *e²* of which are also burned to the lining *a'*. The tubes *e* may be filled with coarse gravel or sand *e'*, that acts as a filter and at the same time as a sustaining-core for the tubes.

The longitudinal lead tubes *d²* and *e* are burned to the transverse tubes *c²* at each point of intersection. So, also, may the tubes *e* be burned to the tubes *d²* at suitable points by a small intermediate lead filling *f*. In this way the entire lead casing of the filter is made in one piece and integral with the barrel-lining *a'*. The solid structure thus formed is capable of resisting all the pressure necessary for filtering the ore without requiring the use of any additional supporting means.

The shape of the filter may obviously be varied. Thus I have shown in Fig. 2 a horizontal filter, while the filter shown in Fig. 7 is convex and that shown in Fig. 8 is concave.

In Fig. 9 the filter is covered with perforated lead plates *g*, burned to one another and to the lining *a'*.

What I claim is—

1. A barrel-filter composed of a barrel having a lead lining, and of a filter having rigid cores and surrounding lead casings made integral with the lining, substantially as specified.

2. A barrel-filter composed of a barrel having a lead lining, and of a filter having rigid intersecting cores and surrounding intersecting lead casings which are made integral with

each other and with the lining, substantially as specified.

3. A barrel-filter composed of a barrel having a lead lining, and of a filter having rigid cores and surrounding flanged lead casings made integral with the lining, substantially as specified.

4. A barrel-filter composed of a barrel having a lead lining, and of a filter having rigid removable cores and lead casings made integral with the lining, substantially as specified.

5. A barrel-filter composed of a barrel hav-

ing a lead lining, and of a filter composed of cores, surrounding lead casings, and hollow perforated filling-tubes, said casings and tubes being made integral with the lining, substantially as specified.

Signed by me at New York city, (Manhattan,) New York, this 18th day of November, 1902.

HENRY R. CASSEL.
